Inventor,

L. Otto P. Meyer

UNITED STATES PATENT OFFICE.

L. OTTO P. MEYER, OF NEWTOWN, CONNECTICUT.

IMPROVEMENT IN MATCH-HOLDERS.

Specification forming part of Letters Patent No. 118,628, dated August 29, 1871; antedated August 25, 1871.

To all whom it may concern:

Be it known that I, L. OTTO P. MEYER, of Newtown, county of Fairfield and State of Connecticut, have invented certain Improvements in the Manufacture of Match-Holders for the Safety-Match; and the following is a specification thereof:

With the view of reducing the cost of my safety-match, I have invented and constructed a match-holder for which the matches may be supplied in common paper boxes or in paper packages, and for which the igniting-surface—the surface for igniting the matches—may be furnished on thick paper; and for greater convenience the match-holder, without being inconveniently large or protective, is constructed so as to present a large surface for igniting matches, and to hold in place against the rear or plate *b* a few reserve sheets of igniting-surfaces.

The Plate III contains the perspective view of holder *D*, embodying my invention, and showing the igniting-surface in its place, and the geometrical drawing of the same, with igniting-surface removed. Figure 1 is a front elevation. Fig. 2 is a side elevation. Fig. 3 is a sectional side ele-

vation, section at the dotted line. Fig. 4 is a plan.

It is optional of what material the match-holder *D* be manufactured; but in the drawing it is represented as being made of sheet metal. The holder is fixed to its place by the ears *a a*. The front plate *b* is provided with the grooves *c c*, which are closed at the bottom end. Between said grooves is to be placed a piece of igniting-surface, so as to cover about the whole front plate *b*. Behind the front plate *b*, and with a little space intervening, is the box *d* in which the matches are to stand and partly to project above. The spring *e* is riveted to the bottom ear *a*, and is designed to hold a few reserve pieces of igniting-surfaces.

I claim as my invention—

The combination of the front plate *b*, grooves *c c*, box *d*, and spring *e*, substantially as and for the purpose hereinbefore set forth.

L. OTTO P. MEYER.
